(57) **CLAIM**

The ornamental design for a pet bed, as shown and described.

DESCRIPTION

FIG. 1 is a perspective view of a pet bed showing my new design;

FIG. 2 is a front elevational view thereof; the rear elevation view being the same;

FIG. 3 is a left side elevational view thereof; the right side elevation view being the same;

FIG. 4 is a top plan view thereof;

FIG. 5 is a bottom plan view thereof;

FIG. 6 is another perspective view thereof;

FIG. 7 is a top, front, left perspective view of the pet bed of FIG. 1, shown closed with the zipper in a second configuration; and,

FIG. 8 is a top, front, left perspective view of the pet bed from FIG. 7, shown folded in the third configuration.

The dash-dash broken lines in the drawings depict portions of the pet bed that form no part of the claimed design.

1 Claim, 8 Drawing Sheets
